UNITED STATES PATENT OFFICE.

WILLIAM A. EUDALY, OF CINCINNATI, OHIO.

BRICK AND TILE KILN.

SPECIFICATION forming part of Letters Patent No. 295,744, dated March 25, 1884.

Application filed January 31, 1884. (No model.)

To all whom it may concern:

Be it known that I, WILLIAM A. EUDALY, a citizen of the United States, residing at Cincinnati, in the county of Hamilton and State 5 of Ohio, have invented certain new and useful Improvements in Brick and Tile Kilns, of which the following is a specification, reference being had therein to the accompanying drawings.

10 My invention relates to kilns for burning brick, tile, and other ceramic products, and has for its object the equal distribution of the heat in the kiln and more economy of fuel and labor than has yet been attained.

15 My invention consists in providing the lower portion of the kiln and floor with a number of compartments, each of which is connected with a smoke chimney or flue situated in the walls or at the sides of the kiln and extending 20 to the top of the same, said chimneys being adapted to be closed at the top or sides by dampers, or by a tile placed on the top.

25 My invention consists, further, in providing a kiln with one or more heat-distributing chambers situated inside of the kiln, and extending from the floor through and to the top of the wares to be burned, said distributing-chambers being closed at the bottom and provided with a number of small apertures.

30 My invention consists, further, in providing a kiln with a number of furnaces of peculiar construction and design, in which the heat for the kiln is generated; also, in providing a kiln-wall with flaring-mouthed openings or eyes, 35 which serve the purpose of connecting the furnaces with fire-bags inside the kiln.

My invention consists, further, in providing the kiln-wall with air-chambers situated at the sides of the mouths or eyes of the kiln, and 40 connected with the same by means of air-passages. Said air-chambers are also connected with the external air by flues or ducts adapted to be controlled by dampers.

45 My invention consists, further, in certain details of construction, which will be more fully hereinafter described, and pointed out in the claims.

Figure 1 is a horizontal sectional view of my improved kiln, taken on the line $x x$ of 50 Fig. 4. Fig. 2 is a similar view of a square kiln embodying the principles of my invention, and showing a series of heat-distributing

chambers. Fig. 3 is a vertical sectional view taken on the line $x' x'$ of Fig. 1. Fig. 4 is a similar view taken on the line $y y$ of Fig. 1. 55

In the drawings, W indicates the outer walls of the kiln, which may be round, square, or of any suitable shape, in which are formed the openings to the furnaces, smoke and draft flues, and air-chambers, which will be more fully described hereinafter. 60

$F F$ are the furnaces, located outside of the wall W , and opening into the kiln by means of eyes or throats of peculiar construction, as will more fully appear. The portion of the 65 wall W which forms the eye of the furnace m is made oval, as shown, so that the volume of gases are condensed or compacted at the center of the throat or eye, after which the products of combustion are permitted to expand 70 into the fire bags or flues by reason of the flaring form of said throat. At this point, and while the products of combustion are expanding into the fire-bags, the heated air from the air-chambers a , located in the walls W , is 75 permitted to enter the throat or eye m through the perforations v and mingle with the gases, and thus insure a complete combustion of the same. The air-chambers a communicate with the external air by means of flues v' , which 80 extend longitudinally through the walls of the furnace, and by which means the air is heated in its passage through said flues. 85

$B B$ are fire bags or flues located near the inner end of the throat m , and are by preference made of a semicircular form in cross-section. These fire-bags extend upward to within a short distance of the arch of the roof, and are provided with openings, through which the heat is distributed into the mass of brick 90 or tile within the kiln.

$s s$ are solid walls of masonry on which the fire-bags are supported, and extend from the throat of the furnace to the mass of masonry A , which supports the walls of the distributing chamber or chambers O . The walls $s s$ are built up from the ground to and through the floor of the kiln a short distance up into the kiln proper, so as to form a low partition-wall, extending from the fire-bags to the distributing-chamber 95 or center of the kiln, and in this way divide the lower portion of the kiln into sections or compartments H . Between the walls of masonry $s s$ is laid an open floor of brick or tile, 100

which, by means of a series of small flues, opens into the large flue or duct *t*, leading from the center of the kiln to the smoke-stacks or chimneys *c*, located within or without the walls of the kiln. The chimneys lead to the top of the kiln, and are so connected with the interior of the same that by placing a tile, *g*, or damper *n* at the top or side thereof, the draft will be closed and the heat thrown to other portions of the kiln where the draft is not closed. The partition walls *s s* being higher than the floor-level, the heated air is caused to rise up into the kiln and pass through the lower portion of the wares before entering an adjoining compartment. In this way, when it is found that one or more parts of the kiln are burning too fast, the heat can be drawn off to other portions, and thus insure a more uniform burning, color, and hardness of the wares.

20 O O are the heat-distributing chambers, the walls of which are supported by the mass of masonry A, which also forms the bottom of the same. The chambers O O extend upward to within a short distance of the roof, and are provided with a series of openings, *i*, through which the products of combustion pass and are distributed evenly throughout the mass of bricks to be burned. Any number of these distributing-chambers may be employed and their 25 location within the kiln be varied; but I prefer to place them as near the center of the kiln as possible, as this arrangement gives the best results and distributes the heat more uniformly throughout the mass of bricks to be burned. It will be noticed that the volume of 30 heat which does not enter the kiln through the openings in the fire-bags B is carried upward to the arch of the roof. The various currents from the different furnaces meet over 35 the distributing chamber or chambers O, and are deflected downward into said chambers. The distributing-chambers, being closed at the bottom and provided with numerous apertures in their sides, permit the heat to pass 40 out on all sides and be evenly distributed 45 through the mass of brick, as before stated.

The operation of my kiln is as follows: The fires being started in the furnaces, the kiln is left open at the top and bottom until it is 50 thoroughly water-smoked; then the tops are closed, leaving the chimneys open. The fuel in the furnaces is supplied with air from the ash-pit and air-chambers at the sides of the fire-box. The rising products of combustion 55 are drawn to the center and downward through the flaring-mouthed openings or eyes in the kiln-wall. In passing through said eyes they are supplied with hot air from the air-chamber in the kiln-wall, which insures complete 60 combustion. The heated air is then taken up the sides of the kiln by means of the fire-bags, the sides of which are provided with a number of openings, thus allowing a portion of the heat to enter the wares before passing to 65 the top of the kiln. The heat passing upward through the fire-bags to the top of the kiln is

drawn downward partially through the wares to be burned and partly through the distributing-chambers. By means of the opening in the sides of the fire-bags and the distributing-chamber, the wares in the top of the kiln are relieved from the great heat to which they are exposed in other kilns, it being carried directly into the middle and lower parts of the kiln, thus insuring a more uniform burning than 75 has heretofore been attained. Should the burner at any time find any part of his kiln burning faster than other parts, which is often the case, the damper at the side or top of the chimneys leading from that portion can be 80 closed and the heat driven to any desired locality in the kiln. This insures uniformity of burning.

In patent to Culbertson and Eudaly, No. 281,029, of July 10, 1883, the air-chambers 85 which supply heated air to effect the combustion of the gases are located within the walls of the furnace and out from the eye of the kiln; but by this construction much heat is lost. I obviate this by placing the air-chambers within 90 the walls of the kiln, so that the heat of the kiln is utilized in heating the air and complete combustion of the gases takes place as they pass into the kiln.

Having thus described my invention and the 95 best means at present known to me for operating the same, I do not wish to be confined strictly to the construction indicated in the drawings and specification, as the same principles may be applied in various ways within 100 wide limits.

I claim as my invention—

1. In a kiln for burning bricks, tiles, &c., a heat-distributing chamber or chambers, O, located within the kiln, closed at the bottom, 105 and provided with a series of apertures, as and for the purpose set forth.

2. A kiln for burning bricks, tiles, &c., provided with one or more heat-distributing chambers, O, located within the kiln and closed at 110 the bottom, and with a furnace or series of furnaces having fire-bags, substantially such as described, whereby a large portion of the heat is carried upward and then downward 115 and distributed to the bricks in the center of the kiln, as set forth.

3. A brick-kiln the floor of which is divided into compartments by walls of solid masonry, said compartments being provided with a perforated floor, under which is a net-work of 120 flues connecting each compartment separately with a chimney situated in or at the sides of the kiln-wall, in combination with the fire-bags B and distributing-chambers O, closed at 125 the bottom, whereby a more equal distribution of heat to the articles to be burned is attained.

4. A brick-kiln the floor and lower part of which are divided into compartments by the walls *s s*, extending above the floor, said compartments being each provided with a flue and chimney adapted to be closed, whereby the 130

heat is made to rise from the floor-level before being distributed to other parts of the kiln.

5. A brick-kiln the walls of which are provided with air-chambers *a*, communicating with the eye or throat of the furnace by ports or flues *v*, and with the external air by means of the flues *v'*, as set forth.

6. In a brick-kiln, the combination of the furnace *F* and fire-bags *B* with the distributing-chamber *O*, as and for the purposes set forth.

7. In a brick-kiln, the combination of the furnaces *F*, fire-bags *B*, distributing-chamber *O*, with the compartments *H* and chimneys *c*, as and for the purposes set forth.

8. In a brick-kiln, the combination of the walls or benches *s*, extending above the floor-level, forming compartments *H*, with the flues *t*, chimney *c*, and dampers *n*, as set forth.

9. The combination of the air-chambers *a*, located within the walls of the kiln, provided with the ducts *v*, with the throat *m*, constructed substantially as described, and the fire-bags *B*, as set forth.

In testimony whereof I affix my signature in presence of two witnesses.

WILLIAM A. EUDALY.
